UNITED STATES PATENT OFFICE.

HARRY F. SHINDEL, OF GLENSIDE, PENNSYLVANIA, ASSIGNOR TO T. A. WILLSON & CO., INC., OF READING, PENNSYLVANIA, A CORPORATION OF PENNSYLVANIA.

SPECTACLE-TEMPLE PIVOT-BUTT.

1,171,895.

Specification of Letters Patent. Patented Feb. 15, 1916.

Application filed June 25, 1914. Serial No. 847,182.

To all whom it may concern:

Be it known that I, HARRY F. SHINDEL, a citizen of the United States, residing at Glenside, in the county of Berks and State 5 of Pennsylvania, have invented certain new and useful Improvements in Spectacle-Temple Pivot-Butts, of which the following is a specification.

My invention relates particularly to two-part spectacle temples of the class shown in Patents Nos. 536,248 and 841,755, issued to T. A. Willson on March 20, 1895, and January 22, 1907 respectively, wherein a separately formed pivot piece is employed in 10 connection with an ordinary temple wire or shaft; and it consists in the improved construction hereinafter fully described and claimed in connection with the accompanying drawings, the main novel feature being 15 an attached pivot piece formed of an end-wise doubled wire as set forth.

Figure 1 shows a completed spectacle temple embodying my invention. Fig. 2 shows a fully formed pivot-butt piece ready 20 to be secured to the temple wire; the latter being indicated in relative position and with a clamping cap-piece strung upon it. Figs. 25 3 and 4 are enlarged views and illustrate respectively the flat and grooved wire employed to produce the pivot-butt as shown in Figs. 1 and 2; Figs. 5 and 6 indicating modified forms of the wire which may be employed. Figs. 7 and 8 indicate modified 30 forms of the finished butt, and Fig. 9 is an edge view of the same.

In the prior patents referred to the separately formed pivot piece employed is made from a stamped sheet metal blank, shaped as required. My improved separately 40 formed pivot piece is simply made from a piece of wire of any suitable cross-section, by doubling the same and adapting the brought-together end portions thereof to engage the temple shaft and the bend portion 45 thereof to form a suitable pivot-eyed end, as will be specifically described by reference to the preferred embodiment of the invention illustrated in the drawings.

A represents an ordinary wire or shaft such 50 as is commonly used for spectacle temples; and B my improved separately formed pivot piece which is attached to an end portion of the shaft A so as to form a pivot-eye butt thereon. This pivot piece B, as shown, is 55 formed from a short piece of wire by bend-

ing it midway of its length so as to double together the end portions for engaging the shaft A between them, the bend of the wire being shaped to form a pivot-eye end.

The term "wire" is used to include a rod 60 or strand of any suitable cross-section, formed by drawing or otherwise; the piece 2 shown in Fig. 4 as of suitable form for the purpose, being a semi-circular grooved wire of uniform metal thickness which when 65 flattened forms a thin strip of the cross-section indicated in Fig. 3, having beveled edges 3, 3 as shown. When this grooved wire is doubled as illustrated, the opposed 70 end portions 4, 4 are adapted to encircle and 75 grip the shaft A with the edges 3, 3 abutting so as to form a tight sleeve thereon; while the bend-portion 5 thereof forms a pivot-eye opening 6.

The pivot-eye 6 may be readily located 75 either in line with the axis of the shaft A, or to one side thereof, as differently shown in Figs. 1, 2, 7, and 8. And the bend-portion 5 may serve as a pivot-eye end in the form indicated in Fig. 7, though it is pref- 80 erably flattened and shaped as indicated in Figs. 1 and 2 to form a better finished pivot-end, with a suitably located stop-shoulder 10 provided therein as is frequently desired.

In attaching my improved pivot piece to 85 the shaft A, the opposing grooved portions 4, 4, are forced together upon the interposed end of the shaft so as to tightly inclose and grip the latter; and are further secured, as shown, by a clamping ring 12 at the ex- 90 tremities thereof. This ring 12 may be merely an encircling band, but is preferably a cup-shaped cap-sleeve as shown, having a central perforation through which the shaft 95 A is passed, and adapted to inclose the ends of the opposing grooved portions 4, 4, of the pivot piece and to form an ornamental finish thereto when properly shaped by a clamp- 100 ing die.

The form of the wire or metal strip em- 100 ployed to produce my improved pivot piece, may obviously be varied from that particu- 105 larly shown and described; Fig. 6 for instance indicating an ordinary spectacle eye-wire as adapted for the purpose, and Fig. 5 a wire of round or square section at the bend portion but specially grooved at its end portions so as to properly engage the shaft A. The described clamping grip upon the latter is ordinarily such as to rigidly secure the 110

pivot piece B thereto, but any possible turning of the shaft on the latter may be readily insured against, as by forming a bend or change in form in the shaft wire in the 5 manner set forth in said Patent No. 841,755. It will be readily understood that the invention thus provides for combining advantages of appearance and strength, with simplicity and economy of construction.

10 What I claim is:

1. A temple pivot-piece of doubled wire, the opposing end portions of the wire having grooved inner faces and the bend-portion thereof forming a pivot eye.
- 15 2. A temple pivot-piece of doubled wire, the opposing end portions of the wire having grooved inner faces and the bend-portion thereof being flattened and forming a pivot eye.
- 20 3. A spectacle temple comprising a shaft portion and a separately formed pivot piece of doubled wire; said shaft portion being interposed between and secured to the parallel end portions of the doubled wire and the bend portion of the latter forming a pivot eye.
- 25 4. A spectacle temple comprising a shaft portion and a separately formed pivot piece

of doubled wire; said shaft portion being clamped between the parallel end portions 30 of the doubled wire and the bend portions of the latter forming a pivot eye.

5. A temple shaft provided with a pivot-piece consisting of a doubled wire having opposing grooved portions which jointly engage the temple wire and a bend-portion forming a pivot-eye temple end. 35

6. A temple shaft provided with a pivot-piece consisting of a doubled wire having opposing grooved portions which jointly engage the temple wire and a bend-portion forming a pivot-eye temple end, and a clamping ring for said grooved portions. 40

7. A temple shaft provided with a pivot-piece consisting of a doubled wire having opposing grooved portions which jointly engage the temple wire and a bend-portion forming a pivot-eye temple end, and a cap 45 for said grooved portions strung upon the temple wire. 50

In testimony whereof I affix my signature in presence of two witnesses.

HARRY F. SHINDEL.
